PHONOGRAPH TURNTABLE

Filed Oct. 11, 1930

UNITED STATES PATENT OFFICE

FREDERICK DIEHL, OF ELIZABETH, NEW JERSEY, ASSIGNOR TO DIEHL MANUFACTURING COMPANY, OF ELIZABETH, NEW JERSEY, A CORPORATION OF NEW JERSEY

PHONOGRAPH TURNTABLE

Application filed October 11, 1930. Serial No. 487,935.

This invention relates to phonograph motors and more particularly to turntables for such motors. The invention has for an object to provide an improved turntable construction including means to prevent transmission to the turntable from its supporting spindle of magnetic hum or gear noise from the spindle driving mechanism. Another object of the invention is to provide a turntable which is inexpensive to manufacture and which will run truly and quietly with its supporting shaft.

It has heretofore been the practice to make the turntable disk of pressed sheet-metal and to make the hub of cast metal which was machined and riveted to the turntable disk. In manufacturing a turntable of this character it is extremely difficult to make the sheet-metal disk run true with the supporting shaft.

According to the present improvement, the turntable, including its hub, is molded in one piece, preferably from phenolic condensation material, in a suitable die which has provision for forming a central shaft-aperture and enlarged recesses at the opposite ends of the shaft-aperture, arranged on an axis truly perpendicular to the face of the turntable disk. After the molding operation is completed, there are fitted in the recesses at the opposite ends of the shaft-aperture, bushings of cork or other comparatively unyielding sound-deadening material adapted to snugly fit the shaft or spindle on which the turntable is mounted; said shaft or spindle being otherwise out of contact with the shaft-aperture in the turntable.

In the accompanying drawings, Fig. 1 is a side elevation of an electric phonograph motor with the turntable shown in section, and Fig. 2 is a bottom plan view of the turntable supporting disk.

The phonograph motor may be of any suitable or usual construction. The one shown is constructed substantially in accordance with the disclosure of the application of James M. Naul, Serial No. 487,951, filed herewith. It comprises a frame 1 in which is journaled a turntable spindle 2 car-

rying a gear 3 meshing with a worm 4 on the motor-shaft 5. The motor-shaft 5 is driven by the induction motor 6 and its speed is governed by the speed-regulator 7.

The shaft 2 has passing through it a pin 8 upon which rests a metal disk 9 having the downwardly struck tongues 10 the ends of which engage the pin 8 and lock the disk 9 to rotate with the shaft 2. Resting upon the disk 9 are one or more washers 11 of cork or other sound-deadening material. The turntable disk 12 including its hub 13 is preferably molded in one piece from phenolic condensation material and is formed with a downturned rim 14 and a slightly depressed upper face 15 to which is cemented a layer of felt 16 the edge of which is guarded against peeling by the shoulder 17 which is disposed slightly above the face 16.

The hub 13 is formed with a central shaft-clearance aperture 18 the ends of which are enlarged to receive the bushings 19 of sound-deadening material having sufficient body to hold the turntable face 16 truly normal to the axis of turntable shaft 2. The bushings 19 are preferably cemented to the turntable hub 13 and are apertured to snugly fit the shaft 2 which is otherwise out of contact with the hub 13. The bushings 19 should be made from a material which is a poor transmitter of sound but which has considerable resistance to deformation under pressure. Cork is found to have the properties desired here, and will hold the turntable true on the shaft 2 and at the same time prevent transmission to the turntable of any noises originating in the motor, such as magnetic hum or gear noise.

Having thus set forth the nature of the invention, what I claim herein is:—

1. In a phonograph, the combination with a turntable shaft, of a turntable disk having a central hub formed with an axial aperture large enough to fit over said shaft without touching the latter, and bushings at the opposite ends of said aperture in engagement with said shaft for holding the turntable true to the shaft, said bushings being formed of a material having poor sound transmis-

sion properties and good resistance to deformation under pressure.

2. In a phonograph, the combination with a turntable shaft, of a turntable disk having 5 a central hub formed with an axial aperture large enough to fit over said shaft without touching the latter, and cork bushings at the opposite ends of said aperture in engagement with said shaft for holding the turn-
10 table true to the shaft.

3. A phonograph turntable comprising a disk and hub molded in one piece from phenolic condensation material, said disk having a depressed upper face and a raised 15 rim, a felt facing cemented to said face with its edge in engagement with said raised rim, said hub having a shaft-aperture enlarged at its opposite ends, and bushings of sound-insulating material cemented in the 20 enlarged ends of said shaft-aperture, said bushings having shaft-apertures smaller than the portion of the shaft-aperture in said hub between said bushings.

In testimony whereof I have signed my
25 name to this specification.

FREDERICK DIEHL.
